CIGARETTE LIGHTER

Kenjiro Goto, Tokyo, Japan, assignor to Mansei Kogyo
Kabushiki Kaisha, Kamiaoki-cho, Kawaguchi-shi,
Saitama-ken, Japan

Filed May 18, 1970, Ser. No. 23,047

Term of patent 7 years

Int. Cl. D27—05

U.S. Cl. D48—27

FIG.1

FIG.2

FIG.3

FIG.4

FIG.5

FIG.6

FIG.8

FIG.7

FIG. 1 is a perspective view of a cigarette lighter showing my new design;

FIG. 2 is a top plan view thereof;

FIG. 3 is an elevational view as taken from the left of FIG. 1;

FIG. 4 is a front elevational view thereof, the rear having the same appearance;

FIG. 5 is an elevational view as taken from the right of FIG. 1;

FIG. 6 is a bottom plan view thereof;

FIG. 7 is a front elevation of the lighter in an operative position;

FIG. 8 is an elevational view of the lighter as taken from the left of FIG. 7.

I claim:

The ornamental design for a cigarette lighter, substantially as shown.
